UNITED STATES PATENT OFFICE.

VANTYLE W. CODDINGTON, OF KANSAS CITY, MISSOURI.

PULLEY.

SPECIFICATION forming part of Letters Patent No. 443,268, dated December 28, 1890.

Application filed January 2, 1890. Serial No. 335,579. (No model.)

To all whom it may concern:

Be it known that I, VANTYLE W. CODDINGTON, a citizen of the United States, residing at Kansas City, in the county of Jackson and State of Missouri, have invented certain new and useful Improvements in Pulleys; and I do hereby declare that the following is a clear and exact description of the same, such as will enable others to make and use the same, reference being had to the accompanying drawings, forming a part of this specification.

The object of my invention is to provide the means for clamping pulleys having either radial spokes or a solid web and similar shaft attachments firmly to a central shaft, and also to enable the separable parts of the hub to adjust themselves to any distortion of the shaft-opening which may occur through the action of the clamping-rods, thus forming a perfect bearing upon all sides of the shaft.

My invention consists in the novel construction and combination of parts, which will first be fully described, and specifically pointed out in the claims.

In the drawings, Figure 1 is a view in perspective of a web-pulley clamped to the shaft by means of the detachable clamping-spokes and separable hub, showing in dotted lines the position of the inner ends of the clamping-spokes when shifted by the action of the clamping-rods. Fig. 2 is a side view of a separable spoked pulley, showing the invention applied thereto. Fig. 3 is a view in perspective of the separable spoked pulley, as seen in Fig. 2, showing the separable hub and a portion of the shaft removed and in alignment with the hub-opening. Fig. 4 is a view in perspective of a web-pulley, showing alternate means for clamping the same to the shaft. Fig. 5 is a vertical sectional view of Fig. 1, showing the spokes upon one side of the web only.

Similar letters of reference indicate corresponding parts in all the figures.

In the construction of my invention as shown in Fig. 1, A represents a web-pulley, the web a' of which extends from the inner side portion of the periphery the required diameter of the pulley, and is provided with a transverse opening a^2 in line with the axis of said pulley to receive and fit loosely the shaft C. Around shaft C, contiguous to one side

of the web a' , is a close-fitting hub or bushing B, which is made with the circular opening b extending in the line of the axis of said hub and of the same radius of curvature as shaft C. The said hub or bushing is separated into four parts $b' b' b' b'$, each part covering a segmental portion of the surface of said shaft. The outer side portion of each part b' of the hub B is cut in a plane in the longitudinal direction of the shaft, each one of which planes is of corresponding extent, and together constitute a series of bearing-faces b^2 . From the face portion b^2 of each separable portion of the hub B, extending an equal distance and radially to the circumference of shaft C, is a series of adjustable spokes D D D D, the contiguous end portions of which spokes bearing upon the faces b^2 of the parts b' of the hub B are squared and correspond in width in the longitudinal direction of shaft C to that of the faces b^2 of said parts b' of the hub. The other end portion of each spoke D is cut away in opposite directions and at a corresponding angle to the radius of the shaft C, so as to form inclines or shoulders $d^3 d^3$, which slope or incline inwardly. Extending through adjacent spokes D D and their shoulders $d^3 d^3$, which are in line and in one direction both above and below the shaft C, are made in parallel lines the perforations $d^4 d^4$. Through the other shoulder d^3 , in line with each other and in a direction at right angles to the perforations $d^4 d^4$, are made the registering perforations $d^6 d^6$ and $d^7 d^7$. Through the perforations $d^4 d^4$ are inserted the separable clamping-rods $f f f f$. Upon one end of each rod is a head f^0 , and the other end screw-threaded and provided with the adjusting-nut f^3 . Through the registering perforations $d^6 d^6 d^7 d^7$ are inserted the separate clamping-rods $f' f'$, each one of which rods is provided with a head f^0 at one end and screw-threaded at the other, and to which end is fitted an adjusting-nut f^3 .

In a transverse direction to and through each one of the spokes D, in the direction of the web a' of the pulley, is made a longitudinal slot d^4 . Through the slots d^4 and into the web a' are inserted the screw-threaded ends of the bolts b^8 , the other ends of which bolts are provided with bolt-heads in the usual manner.

In Figs. 2 and 3 I have shown a spoked

pulley in which the spokes are also a constituent part of the means for clamping the pulley to the shaft. In said figures the periphery of the pulley is separated into two parts, and the means for clamping the spokes to the shaft are the same as in Fig. 1, the spokes G G in said Figs. 2 and 3 being extended to the periphery of the pulley. In said Figs. 2 and 3 I have shown the web in a modified form, as at II, extending from the inner side portion of the periphery a short distance in the direction of shaft C and increased in the line of the spokes G. Through the ends of each one of the spokes G near said periphery is made the radial slot h, in line with said web, to receive said extended portion of the web.

In the application of the invention to web-pulleys shown in Fig. 4 I may dispense with the clamping-rod f f in one direction, and in their place attach to the web fixedly, or to the periphery, as preferred, on both sides of shaft C, the spoke-spreading blocks A' A², which extend between the outer adjacent ends of the spokes D D, which are clamped by the rods f' f² and retain said spoke the proper distance apart. The corner portions a² of said ends are cut away in a corresponding degree to the inclination of the sides of spokes D, upon which portions the spokes bear and have free movement. Said blocks A' A² extend to the rods f' f², but all that is necessary is to afford the bearing for the spokes D D.

In securing the pulleys to the shaft the several parts of the hub are placed upon the shaft in regular order—first the separate parts b' and then the spokes D—the clamping-bolts inserted, and the nuts turned on the rods f f' f², so as to draw the bearing ends of the spokes on the faces b' in the direction of shaft C. In this operation the tightening of one clamping-rod has the effect to change the relation of the bearing-surfaces of the end of each spoke to the shaft, and bring to bear an unequal pressure upon each face of the separable parts of the hub, which parts slip around

the shaft in the direction of the greatest pressure and adjust themselves to equalize the bearings.

In Fig. 1 I have shown in dotted lines the result of the action of the clamping-rod f' f², which distort the position of the lower ends of the spokes D D, the movement of which is resisted by the rods f f. To meet this distortion, as the separable parts of the hub slip on shaft C the contiguous end portions of the spokes which bear on the faces b' of the separable parts b' of the hub also shift in position, and the pressure upon the shaft is made direct as the adjustments of the clamping-rod are successively made.

In clamping web-pulleys to the shaft the slots d' in the spokes permit the spokes to be moved without removing the fastening-screws.

Having fully described my invention, what I now claim as new, and desire to secure by Letters Patent, is—

1. The combination, in a separable pulley, with the rim, of a series of radial spokes, a central shaft, and a hub or bushing on said shaft, composed of separable parts corresponding in number to said spokes, having the inner side portion of each part covering a portion of the surface of said shaft and its outer face portion in a plane longitudinal to said shaft, each one of said spokes having a squared inner end bearing upon one face of said bushing and each spoke having opposite shoulders, clamping-rod in registering perforations of said spokes, and adjusting-nuts on said rods bearing upon said shoulders, substantially as and for the purposes described.

2. A pulley having shaft-clamping parts, consisting of a series of radial spokes adjustably clamped together in sets, and radial spoke-spreading blocks extending between said adjustably-clamped spokes, substantially as and for the purpose described.

VANTYLE W. CODDINGTON.
